HOUSING FOR AN ALARM UNIT FOR SWIMMING POOLS OR THE LIKE

Lawrence V. Lohr, 15344 Weddington St.,
Van Nuys, Calif. 91401

Filed Apr. 10, 1969, Ser. No. 16,670

Term of patent 14 years

Int. Cl. D29—02

U.S. Cl. D72—1

FIG.-1

FIG.-2

FIG.-4

FIG.-3

FIG. 1 is a front elevation view of my new housing for an alarm unit design;

FIG. 2 is a top view thereof;

FIG. 3 is a top perspective view on an enlarged scale, the housing being fragmentarily shown for convenience of illustration;

FIG. 4 is a perspective view thereof.

I claim:

The ornamental design for a housing for an alarm unit for swimming pools or the like, substantially as shown and described.
